UNITED STATES PATENT OFFICE

ALISTER DUNCAN MACGILLIVRAY, OF SANTO DOMINGO, DOMINICAN REPUBLIC

SOLE STRAIGHTENER

Application filed February 8, 1930, Serial No. 426,893, and in Great Britain January 15, 1930.

This invention relates to sole straighteners, that is to say, to devices for preserving the shape of boots and shoes when they are not being worn.

5 An object of the invention is to provide an efficient device for the said purpose which shall be cheap in construction, efficient in operation, and readily adjustable for use with soles of greatly varying sizes. Another object is to provide such a device comprising a metal body adapted to be attached outside and under the sole of the boot or shoe and so constructed as to keep the sole in a flat condition when thus attached. Another object is to provide such a device which shall be partly collapsible when not in use for convenience of storage or transport. Other objects and advantages of the invention will become apparent from the following description when read in conjunction with the accompanying drawings.

Figure 1 is a side elevation of one form of the device.

Figure 2 is a plan of the device illustrated in Figure 1 in position for use.

Figure 3 is a side elevation corresponding with Figure 1 but representing the device in a collapsed condition.

Figure 4 is a plan of the device in the condition illustrated in Figure 3.

Figure 5 is a plan representing a modified construction of the device illustrated in Figures 1 to 4.

Figure 6 is a side elevation of another modification.

Figure 7 is a plan of the device illustrated in Figure 6.

Figure 8 is a plan of a third example of construction.

Figure 9 is a section of the device illustrated in Figure 8, taken on the line 9—9 in Figure 8.

A metal body A, which may be stamped and bent out of a sheet of metal, or constructed of steel wire, is provided with arms D, projecting beyond its periphery and terminating in means for engaging the edges of the sole the extent of the said projection being adjustable, preferably by means of slotted connections.

In the embodiment illustrated in Figures 1 to 4, the body of the device A consists of an upwardly curved strip of spring metal, the front end of which is turned up to form an arcuate wall a^1 , the height of which is approximately that of the normal thickness of a boot sole, with a reverted flange a^2 at the top thereof to fit over the front of the sole. Near the other end of the body A are four or other number of holes a^3 , in any one of which a stud or rivet C can be secured. Two overlapping arms D, D^1 , are longitudinally slotted at d^3 to engage this stud C, on which they are adjustable both laterally and angularly, so that they can be turned out in opposite directions, that is, to project at right angles from the body A, or at any other angle. At the free end of each arm (D, D^1) is a hook or clip (E, E^1) adapted to engage the edge of the boot sole. When the hooks E, E^1 are thus engaged with the sides of the sole, and the wall a^1 engaged with the front of the sole, the resilient pressure between the upper part of the curved body A and the sole tending to straighten out the curve of the body A causes the wall a^1 to draw down the toe of the boot, thus counteracting any tendency of the sole to turn up at the toe. The distance between the two clips E, E^1 can be varied by moving the slotted parts of the arms relatively to the stud C within the limits of the slots d^3 to fit on wide or narrow soles, and each of the said arms can be swung about the stud C to enable its clip to engage any desired part within its reach of the length of the side of the sole. The provision of the holes a^3 for the attachment of the stud C enables the effective length of the device to be adjusted according to the length of the sole to which the device is to be applied. For storage or transport, the arms D, D^1 can each be pushed towards the body A so far as their slots d^2 permit, and placed in overlapping alignment with each other as represented in Figures 3 and 4.

In the modification illustrated in Figure 5, the body A is made of steel wire. The arms D, D^1 may also be made of steel wire.

The body A as represented in Figures 6 and 7 comprises a narrow waist portion a^4 .

which is doubly bent as seen clearly in Figure 6 to obtain the spring pressure on the straightening out of the body when the clips or hooks are engaged with the sole. The 5 front of the body is provided with an integral hook a^5 to clip over the front of the sole. At its rear end the body forms a crossbar a^6 , in which are secured two studs C^1 , C^2 , on which arms D , D^1 are laterally and angularly adjustable in the same way as that described with reference to Figures 1 and 2. For storage or transit, the arms may either be turned back as seen in Figure 6, or turned forward to nestle between the crossbar and 10 the main front portion of the body A.

Referring now to Figures 8 and 9, the body A is a flat disc of metal pierced by at least three radial slots, F, G, H. Arms D, D^1 , D^2 are each provided with a stud passing through the respective slots, on which stud the arm can swivel, and the stud is also adjustable longitudinally of the slot. It is of course immaterial as to whether the studs (C , C^1 , C^2) are on the arms and the slots in 15 the body, or the studs are fixed in the body and the arms slotted to embrace the shanks of the studs. Each arm terminates in a hook, these hooks being indicated at E, E^1 , and E^2 , and each arm has a doubly bent portion d^4 20 in order to cause the disc A to press against the sole when the said hooks are engaged with the edges of the sole. In use, the hook E^2 is sprung over the front of the sole and the hooks E and E^1 are sprung over the edges 25 of the sole at opposite sides thereof. When the device is not in use, each arm is pushed in as far as the slots F, G, H permit, when the hooks E, E^1 , and E^2 will lie closely 30 against the periphery of the disc A, and the device can then be packed in a small box of circular shape, or a number of such devices can be stacked in a column of substantially 35 cylindrical form.

It will be observed that in all the examples 40 described the arms are adjustable not only in the direction of their length but also angularly in relation to the body of the device, so that a single sole straightener can be fitted to any of a number of soles of greatly different 45 sizes, and the stowing of the sole straighteners in a small space is facilitated by the method of attachment of the arms described.

While I have herein described and illustrated examples of construction whereby all 50 the aforesaid objects of the invention can be accomplished, it is obvious that various changes could be made in the shapes of the parts of the device without departing from the principle of the invention, and it will be 55 understood that the invention is not limited to the exact constructions shown, but includes any variations that may fairly fall within the scope of the following claims.

What I claim and desire to secure by Letters Patent of the United States is:—

1. In a sole straightener, a metal body adapted to be attached outside the sole, means at one end of said body to engage over the front of the sole, a stud at the other end of said body, a plurality of longitudinally slotted arms embracing said stud and each adapted to swing on said stud into a position transverse to said body, said arms also being adapted to be collapsed into positions in alignment with each other and with said body and each of said arms being provided with means to engage the edges of the sole. 70

2. In a sole straightener, a metal body adapted to be attached outside the sole, means at one end of said body to engage over the front of the sole, said body having at its other end a crossbar, two studs in said crossbar, two longitudinally slotted arms each pivotally and reciprocably engaging one of said studs, said arms being provided with means to engage the edges of the sole. 75

3. In a sole straightener, a curved body of spring metal adapted to be attached outside the sole, the front end of which body is turned up to form an areuate wall and a reverted flange, the rear end of said body being perforated with holes, a stud adapted to be secured in any one of said holes and longitudinally slotted arms pivotally and reciprocably engaging said stud, each of said arms being provided with means to engage the sole at one side thereof. 80

4. In a sole straightener, a substantially circular metal body adapted to be attached outside the sole and provided with three arms longitudinally and angularly adjustable in relation to said body, said arms being provided with means to engage the edges of the sole and being bent in such manner as to exert a resilient pressure on the sole. 85

5. In a sole straightener, a metal body adapted to be attached outside the sole, a pin on said body, a plurality of longitudinally slotted arms each provided at its outer end with means to engage the sole, each of said arms engaging said pin in such manner as to be pivotable around said pin and to be adjustable longitudinally on said pin. 90
